ANTENNA

Ernest A. Martinelli, Arlington, Mass., assignor, by mesne assignments, to the United States of America as represented by the Secretary of War

Application August 1, 1945, Serial No. 603,294

2 Claims. (Cl. 250—33.65)

1

This invention relates to antennas for radio object-locating systems and particularly to means for obtaining a radiation pattern closely approximating the relationship $K \csc^2 \theta$ in one plane, where θ is the angle measured from the axis of the radiating means and K is a constant.

In certain airborne radio object-locating systems, for example, P. P. I. (plan position indicating) apparatus, it is desirable that the distribution of energy in a vertical plane throughout a relatively wide angle be such that the variation of energy density versus the radiation angle is a cosecant-squared function. This provides relatively constant echo strength for targets located on the earth or other surface regardless of whether the target is distant or close in, and it eliminates the need of tilting the antenna to obtain adequate coverage of the area under observation.

An object of the present invention is to afford a cosecant-squared radiation pattern by the use of a modified paraboloidal antenna. Another object is to achieve simplicity in the design of such an antenna. Still other novel features and advantages will be apparent from the following disclosure of the invention.

In the drawings:

Fig. 1 is a side elevation of an antenna embodying the invention;

Fig. 2 is a front elevation of the antenna;

Fig. 3 is a perspective view illustrating the development of the modified paraboloidal reflecting surface of the antenna; and

Fig. 4 is a partially diagrammatic view showing the manner in which the antenna may be mounted in an airplane and the radiation pattern which it produces.

Referring to Figs. 1 and 2, the radiating element or feed 10 may be constructed and located in a conventional manner. The reflector 11 in the present instance is formed in two parts. The lower portion 12 extending below the level of the radiator 10, as viewed in Figs. 1 and 2, is a paraboloidal surface having its focal point at the apparent center of radiation of the radiating source 10. The upper portion 13 of the reflector 11 extending above the level of the radiator 10 is a modified paraboloidal surface, the configuration of which will be described in detail herein-after.

Fig. 4 illustrates the manner in which the antenna of Figs. 1 and 2 is mounted in the nose of an airplane 15 so that it may scan the area disposed beneath the aircraft. The type of radiation pattern which is produced by this novel

antenna is indicated in broken lines and closely approximates the relation $\csc^2 \theta$ where θ is the radiation angle measured from the radiation axis $\theta=0$. It will be appreciated that the P. P. I. type of scan for which the present invention is particularly designed is accomplished by rotation of the antenna about a vertical axis in a well-known manner. Distant objects located in the area which is being scanned are subjected to 10 radiant energy by a portion of the radiation field having relatively greater intensity than that portion of the radiation field which strikes objects closer in, whereby substantial uniformity in the strength of received signals is achieved.

15 The development of the modified paraboloidal surface is illustrated in detail in Fig. 3. The surface shown in this view includes a lower part A—B—C—G comprising a half-section through the vertex or nose portion of a paraboloid which has its focus at point F. A plane passed through the point F and vertex B will intersect the paraboloid surface along the parabola A—B—C. The ends of this parabola are shown extended along the broken lines to intersect the latus rectum D—E of the parabola. Now let it be assumed that the parabola A—B—C lying in the aforesaid plane passed through the focus F is rotated upwardly through substantially 90° about the latus rectum D—E as an axis, moving along the circular path indicated in Fig. 3 to a position A'—B'—C' and thereby generating a barrel-like surface having a parabolic stave.

20 When viewed from the side, the modified paraboloidal surface has a configuration similar to that shown in Fig. 1 in which the lower portion 12 is parabolic and the upper part 13 appears to lie along a circular arc having its center at the focal point of the paraboloid and with a radius through the middle of the reflector equal (to the nearest half wavelength) to the focal length of the paraboloid. When viewed from the front, this surface appears as shown in Fig. 2, in which the lower part 12 has a circular outline and the upper part 13 is parabolic. The upper portion 13 of the reflector 11 tends to concentrate the radiation directly downward, while the lower portion 12 tends to concentrate the radiation ahead of the reflector. The combination of these effects is such as to produce the $\csc^2 \theta$ radiation pattern as described. It should be noted that modifications can be made in the shape of the reflector 11, if desired, to alter the cosecant-squared pattern.

25 While I have illustrated and described a selected embodiment of my invention, it is

apparent that variations and modifications may be made by persons skilled in the art without departing from the spirit of the invention. Hence I do not desire to limit the scope of the invention to the disclosed details but wish to avail myself of all improvements and modifications within the purview of the following claims.

I claim:

1. In an antenna for producing a cosecant-squared radiation pattern, a reflector comprising a portion having a paraboloidal reflecting surface and another contiguous portion having a barrel-shaped reflecting surface with a parabolic stave. 10
2. In an antenna for producing a cosecant-squared radiation pattern, a reflector comprising, in combination, a portion having a reflecting surface shaped as a part of a paraboloid including the vertex thereof and disposed on one side of a 15

plane passed substantially through the focal point and said vertex, and another portion having a reflecting surface generated by rotating the parabolic contour formed at the intersection of said paraboloid with said plane through substantially 90° along a circular path about the latus rectum of said parabola as an axis.
